UNITED STATES PATENT OFFICE.

CHESTER A. HERLE, OF ROCHESTER, NEW YORK.

COIN-ACTUATED APPLIANCE.

1,330,870.

Specification of Letters Patent.

Patented Feb. 17, 1920.

Application filed April 1, 1919. Serial No. 286,710.

To all whom it may concern:

Be it known that I, CHESTER A. HERLE, a citizen of the United States, and resident of Rochester, in the county of Monroe, and 5 State of New York, have invented certain new and useful Improvements in Coin-Actuated Appliances, of which the following is a specification.

The present invention relates to coin 10 actuated appliances and more particularly to the type employing a chute combined with a figure having a movable part actuated by the coin passing through the chute, an object of this invention being to associate with said 15 movable part, another movable part which has a normal position from which said second movable part is shifted by impact with the coin actuated movable part, thus permitting the two movable parts to coöperate for the purpose of amusement. Another 20 object of the invention is to associate with the chute a toy bank which is novel in construction and inexpensive to manufacture while not being liable to get out of order. 25 Still another object of the invention is to provide a connection between the coin actuated movable part and a device which is engaged by the coin, said connection permitting the movable part to be moved independently of the coin engaged part so 30 that the coin engaged part cannot be controlled through the movable part and can act as a coin trap to prevent the discharge of coins through the coin chute.

35 To these and other ends the invention consists of certain parts and combinations of parts, all of which will be hereinafter described, the novel features being pointed out in the appended claims.

40 In the drawings:

Figure 1 is a vertical section through a bank embodying the present invention;

Fig. 2 is a section on the line 2—2, Fig. 1, 45 part of the bank being shown in side elevation;

Fig. 3 is a front view of a bank; and

Fig. 4 is a section on the line 4—4, Fig. 2.

In the present embodiment of the invention, the bank casing is formed of three sheet 50 metal parts, one of said parts consisting of the side walls 1 and 2 and the top wall 3, the side walls being projected forwardly to provide a bulged lower portion to the bank and the front and rear edges of the side and 55 top walls being provided with inwardly turned flanges 4 and 5. Another of the

sheet metal parts comprises a rear wall 6, a bottom wall 7 and the lower portion 8 of the front wall, these walls being received within the flanges 4 and 5 and being secured 60 to the first described sheet metal part by tongues 9 projected from the edges of the second described sheet metal part and passing through openings in the side walls 1 and 2. To further secure the parts together, the 65 lower edge of the side walls 1 and 2 are also bent at 10 around flanges 11 formed on the sides of the bottom wall 7. The third metal part consists of the upper portion 12 of the front wall having two rearwardly extending 70 flanges indicated at 13 and 14 and lying between the flanges 4 and 5, the flange 13 abutting the side wall 2 while the flange 14 is spaced from the side wall 1 to provide a coin chute 15, the upper end of 75 this chute forming wall 14 abutting the top wall 3 to one side of a coin receiving slot 16 in the top wall. The lower edge of the upper portion 12 of the front wall rests upon the rearwardly turned portion 80 of the lower part 8 of the front wall in front of a flange 17 formed at the upper portion of the lower part 8 of the front wall. At its rear edge, the chute forming wall 14 is provided with an outwardly extending 85 rib 18 which abuts the inner face of the side wall 1 so as to hold the wall 14 in properly spaced relation to the side wall. The coins in the coin bank may be removed through an opening in the bottom wall 7 and this opening 90 may be closed by a sheet metal plug 19 which carries oppositely extending spring fingers 20, one of which is adapted to be passed through a recess 21 in the side of the opening through which the coins are removed, the spring fingers then being turned 95 to engage over the flange 22 about the opening in the bottom wall, thus locking the closure in place.

Associated with the coin chute is a coin 100 trap in the form of an arm or detent 23 mounted to turn upon a shaft 24 which is journaled in the front wall 12 and in an arm 25 extending from the flange 14. This shaft has rigidly secured to it, an arm 26 which 105 extends from the shaft in a direction opposite from the arm 23 and rests on the extension 27 on said arm 23 in order to hold the arm 23 in the path of a coin passing through the chute. The arm 23 when engaged by the coin swings downwardly to the dotted line position shown in Fig. 1 per-

mitting the coin to pass into the bank. Normally the arm 23 lies against the lower edge of the flange 14 under the action of the arm 26 which performs the function of a weight. Should however, the bank be inverted the arm 26 will swing to the dotted line position shown in Fig. 1 without producing any movement of the arm 23, due to the fact that the arm 23 can turn loosely on the shaft 24 in one direction.

For the purpose of amusement the coin trapping device controls movable parts on the exterior of the bank. In the illustrated construction the upper part of the front wall of the bank is provided with two figures, one representing "Uncle Sam" and the other a German. One of these figures is provided with a movable part in the form of an arm 28 which is rigidly secured to the shaft 24 so as to turn with said shaft and the arm 26, while the other figure has a movable part in the form of a movable head 29 pivoted at 30 behind a plate 30° and normally lying under the action of gravity in the forward direction so as to be in the path of the movement of the movable part 28. When the coin passes through the chute it engages the arm 23, actuates the latter and turns the shaft 24, thus swinging the outer end of the arm 28 in an upward direction causing said arm to impinge the movable part 29 which is then swung rearwardly under the force of the impact, returning again to its normal position under the action of gravity.

From the foregoing it will be seen that there has been provided a coin bank which may be inexpensively made from sheet metal to provide therein a coin chute. There has been associated with the coin chute a coin trapping device which also controls a movable part on the outside of the bank, this movable part having a lost motion connection with the coin trapping device so that the coin trapping device may not be controlled through the movable part. The movable part acts upon a gravity operated part under the influence of a coin and provides an amusement device in connection with the coin chute.

What I claim as my invention and desire to secure by Letters Patent is:

1. A coin receptacle having a coin chute, a movably mounted part on the receptacle, a coin trapping device having a portion arranged to be engaged by a coin passing through the chute to effect the movement of the movable part and to prevent the discharge of the coin from the chute, said

movably mounted part having a connection 60 with the coin trapping device which will permit the movably mounted part to move in one direction without moving the coin trapping device.

2. In combination with a coin chute, a coin trapping device engaged and moved by a coin passing through the chute, and a movable part moved by the coin trapping device and having a connection with said device which will permit the part to be moved in one direction without moving the coin trapping device.

3. In combination with a coin receptacle having a coin chute; a movable part arranged on the exterior of the receptacle, and a coin trapping device arranged within the receptacle to be engaged and moved by a coin passing through the chute to move the movable part, said device having a connection with the movable part which will permit the movable part to be moved in one direction without moving the coin trapping device.

4. In combination with a coin receptacle having a coin chute; a pivoted part having a portion arranged on the exterior of the receptacle and a portion arranged within the receptacle, and a second pivoted part having an axis common to the axis of the first named pivoted part and extending into the coin chute to be engaged by a coin passing through the chute, the first named pivoted part being moved in one direction by the second named pivoted part when the latter is engaged by a coin, but having a connection with the coin engaged part which will permit the first named part to move in the other direction independently of the coin engaged part.

5. In combination with a coin chute, two movable parts, one of which has a portion arranged to be shifted by a coin passing through the chute, and the other of which has a position to which it is moved by gravity and from which it moves by impact with the other movable part when the latter is moved by a coin.

6. In combination with a coin chute, a wall arranged at a plane at right angles to a coin passing through the chute and having two movable parts both held in normal positions by gravity, one of said parts being operable by a coin passing through the coin chute and the other of said parts being engaged and moved by the coin moved part when the latter is shifted by a coin.

CHESTER A. HERLE.
